CLAIM

The ornamental design for storage box with hinged lid, as shown and described.

DESCRIPTION

FIG. 1 is a perspective view of a storage box with hinged lid showing our new design;

FIG. 2 is a front elevation thereof;

FIG. 3 is a rear elevation thereof;

FIG. 4 is a left side elevation thereof; the right side elevation being a mirror image thereof;

FIG. 5 is a top plan view thereof; and

FIG. 6 is a bottom plan view thereof.

FIG. 1

FIG. 2

FIG. 3

FIG. 4

FIG. 5

FIG. 6
